SWEATPROOF BURIAL VAULT

Robert A. Burns, Los Angeles, Calif.

Application December 13, 1934, Serial No. 757,315

12 Claims. (Cl. 72—7)

This invention relates to improvements in sweatproof burial vaults. Heretofore, it has been common practice in constructing burial vaults to so form the vault that it has a solid wall formed of concrete. Because of the fact that the concrete is, to a certain extent, porous, it is possible for moisture to permeate the walls of the vault and thus of its interior. This results in the vault "sweating". Efforts to render the vault water-
10 proof have been made with considerable difficulty.

An object of the present invention is to provide a burial vault which is of such construction that moisture cannot pass through the walls of the vault or its cover and enter the vault.

15 Another object of the invention is to provide a burial vault having bottom, side, and end walls, and a cover, which are hollow in that there are air spaces therein, the faces of which are coated with a waterproofing material such as asphaltum, rendering the vault impervious to moisture, and to provide a means for draining the spaces or chambers in the walls so that in the event that moisture should pass through the outer portions of the walls of the vault and enter the air spaces 25 it may readily drain therefrom and cannot pass into the interior of the vault.

Another object of the invention is to provide a burial vault having the above mentioned characteristics which is of relatively simple and durable 30 design and construction.

With the foregoing and other objects in view, which will be made manifest in the following detailed description, and specifically pointed out in the appended claims, reference is had to the accompanying drawings for an illustrative embodiment of the invention, wherein:

Fig. 1 is a longitudinal section through the improved burial vault.

Fig. 2 is a horizontal section taken substantially upon the line 2—2 upon Fig. 1.

Fig. 3 is a vertical, transverse section through the vault taken substantially upon the line 3—3 upon Fig. 1.

Fig. 4 is a partial view in vertical section taken 45 through an end wall of the vault, illustrating details of construction.

Fig. 5 is a view similar to Fig. 4, the view having been taken through a side wall of the vault.

Referring to the accompanying drawings, 50 wherein similar reference characters designate similar parts throughout, the improved vault consists of an outer concrete container having a bottom wall 10, side walls 11 and 12, and end walls 13 and 14. This outer container may be formed 55 in any preferred manner, it being preferable,

however, to pour the concrete over that of the above mentioned walls or integral with each other. Small openings 15 and 16 are formed in the bottom wall 10 adjacent the end walls 13 and 14. These may be formed by positioning small tubes or pipes in the mold for the concrete in pouring the outer container or they may be formed by cores that are removed after the concrete has set. The bottom, also, has additional apertures 17 and 18 formed therein corresponding 5 to the apertures 15 and 16, except that these apertures are arranged adjacent the side walls 11 and 12. The side and end walls have their tops recessed on their inner faces, as indicated at 19.

Inner walls are provided in the form of individual concrete slabs, the inner bottom wall being indicated at 20 and the inner end walls indicated at 21 and 22, while the inner side walls are indicated at 23 and 24. The inner bottom wall 20 has embossments formed on its bottom surface, 20 which bear on the bottom 10 of the outer container. These embossments are indicated at 25 and hold the major portion of the inner bottom wall 20 in spaced relation to the bottom 10, defining one or more air spaces 26 therebetween. In 25 a similar way, the end walls 21 and 22 have embossments 27 and, in a like manner, the side walls 23 and 24 have embossments 28. The uppermost embossments on the side and end walls 21, 22, 23, and 24 are slightly thicker than the bottom embossments thereon so that these embossments are partially recessed in the recesses 19 formed on the interior of the outer container. The lowermost embossments on the side and end walls have recesses 30 formed therein which will accommodate 35 the tubes used to form the apertures 15, 16, 17 and 18, or, in the event that no tubes are used, these recesses will register with the apertures designated by the above reference characters.

The side walls 23 and 24 extend from end to 40 end in the outer container. The inner end walls 21 and 22 fit between the ends of the side walls 23 and 24 and are so designed that when their upper embossments are fitting in the recesses 19 their bottom edges will be slightly spaced from 45 the bottom 10 of the outer container. The inner bottom 20 is of such size that when positioned within the side and end walls on bottom 10 it will be slightly spaced from the inner side and end walls.

To assemble the inner walls in the outer container the interior surfaces in the outer container are coated with a coating of asphaltum or like waterproofing material. The outer faces of the inner walls are likewise coated. The inner side 55

and end walls are then positioned against their corresponding walls of the outer container and the inner bottom 20 is then dropped in place. The small clearance between the inner side and 5 end walls and the bottom 10 and the small clearance between the edges of the inner bottom wall 20 and the inner side and end walls may be filled by pouring asphaltum therein, as indicated at 31.

The uppermost embossments on the inner side 10 and end walls which are recessed in the walls of the outer container have apertures 32 formed therein. These are preferably provided with small sections of metal tubing 33 which are telescopically slideable. The top edges of the inner 15 side and end walls are preferably grooved as at 34, this groove being located preferably somewhat higher than the top edge of the outer container, indicated at 35.

The cover for the burial vault has an outer 20 cover 36 of any preferred design preferably formed of a single piece of concrete. It has downwardly extending flanges 37 at its sides and ends, these flanges having beads 38 therein adapted to enter the grooves 34, and seating edges 39 adapted 25 to seat on the top 35 of the outer container. Within the cover there is disposed a cover lining preferably formed of two sections 40 and 41 extending longitudinally of the cover. The side edges of the lining sections are recessed as indicated at 42 in the side flanges on the cover, as 30 clearly shown in Figs. 4 and 5. The end edges of the lining sections merely abut against the ends of the cover. These sections, on being assembled in the cover, have the planes of 35 their bodies upwardly and inwardly inclined. The small space that may be present between the abutting surfaces of the lining sections may be filled with cement or asphaltum so that the lining sections of the cover will be effectively 40 keyed in the outer cover 36.

It will be noted that major portions of the lining sections are disposed in spaced relation to the cover, defining air spaces 43 therebetween. Prior to the assembly of the lining sections and the 45 cover, the under surface of the outer cover 36 and the top surfaces of the lining sections are coated with asphaltum or other waterproofing material. As a means for draining these air spaces ports 47 are formed in the flanges 37. These may lead to the outside of the cover or they 50 may communicate solely with ports 48 which extend downwardly through the beads 38 so as to register with tubes 33. In the preferred form of construction both ports 47 and 48 are employed 55 although either set of ports may be omitted. Ports 48 are preferably lined with small tubes 49 capable of telescoping within tubes 33.

It will be understood that the inner walls of the container are assembled with the outer container 60 at the place of manufacture and likewise, the lining sections of the cover are assembled with the outer cover at the factory. When the coffin has been placed within the vault the tubes 33 are caused to slide upwardly in their apertures so that 65 they project upwardly through groove 44. Asphaltum can then be placed in the groove around these tubes and cement may be applied to the top edge 35 of the outer container. The cover is then applied with the tubes 49 entering tubes 35. As 70 the cover seats itself it squeezes and spreads the asphaltum in groove 34 and the cement on edge 35. The vault is then in condition to be lowered into the grave.

It will be noted that as the inner surfaces of 75 the outer container are coated with asphaltum

and the inner surface of the cover 36 is, likewise, coated, moisture tending to penetrate the outer container and cover will be effectively halted by this waterproofing coating. Should the moisture, however, penetrate the coating and enter the air spaces it may readily drain therefrom. It may flow from air spaces 43 through ports 47 and 48, through the air spaces between the inner side walls and end walls and the outer container and drain through the apertures 15, 16, 17, and 18. As the inner walls and lining sections have the waterproofing asphaltum applied to their outer faces, there is no danger of moisture penetrating and entering the interior of the vault. Consequently, any "sweating" of the vault is effectively 15 prevented.

From the above described constructions it will be appreciated that the improved burial vault is of relatively simple and durable construction. "Sweating" is effectively prevented by making the 20 walls of the vault hollow and waterproofing the surfaces defining the air spaces therein and making provision for suitable drains to drain off any moisture that should, perchance, enter these air spaces.

Various changes may be made in the details of construction without departing from the spirit or scope of the invention as defined by the appended claims.

I claim:

1. A sweatproof burial vault comprising a concrete container having a cover, the walls of the container and the cover being hollow, a waterproofing coating applied to the surfaces defining the spaces in the walls, and means providing for 35 draining the spaces in the walls.

2. A sweatproof burial vault comprising a concrete container having a cover, the walls of the container and the cover being hollow, a waterproofing coating applied to the surfaces defining the 40 spaces in the walls, and means providing for draining the spaces in the walls and in the cover.

3. A sweatproof burial vault comprising a concrete container having a cover, the walls of the container and the cover being hollow, a waterproofing coating applied to the surfaces defining the spaces in the walls, means providing for draining the spaces in the walls, and means for draining 45 the cover through the spaces in the walls.

4. A sweatproof burial vault comprising an outer container, inner side, bottom and end walls disposed against the side, bottom, and end walls of the outer container, the majority at least of the inner walls having embossments engaging the outer container to hold the major portions of the inner walls in spaced relation to the outer container to define air spaces therebetween, and means providing for drainage of the air spaces.

5. A sweatproof burial vault comprising an outer container, inner side, bottom and end walls disposed against the side, bottom, and end walls of the outer container, the majority at least of the inner walls having embossments engaging the outer container to hold the major portions of the inner walls in spaced relation to the outer container to define air spaces therebetween, a waterproof coating applied to the surfaces defining the air spaces, and means providing for drainage of the air spaces.

6. A sweatproof burial vault comprising an outer container, inner side, bottom, and end walls disposed against the side, bottom, and end walls of the outer container, means for holding the major portions of the inner walls in spaced relation to the outer container to define air spaces

therebetween, and means providing for drainage of the air spaces.

7. A sweatproof burial vault comprising an outer container, inner side, bottom, and end walls disposed against the side, bottom, and end walls of the outer container, means for holding the major portions of the inner walls in spaced relation to the outer container to define air spaces therebetween, a waterproof coating applied to the surfaces defining the air spaces, and means providing for drainage of the air spaces.

8. A sweatproof burial vault comprising an outer container, inner side, bottom and end walls disposed against the side, bottom, and end walls of the outer container, the majority at least of the inner walls having embossments engaging the outer container to hold the major portions of the inner walls in spaced relation to the outer container to define air spaces therebetween, some of the embossments on the side and end walls being recessed in the walls of the outer container.

9. A sweatproof burial vault comprising an outer container, inner side, bottom, and end walls disposed against the side, bottom, and end walls of the outer container, the majority at least of the inner walls having embossments engaging the outer container to hold the major portions of the inner walls in spaced relation to the outer container to define air spaces therebetween, some of the embossments on the side and end walls being recessed in the walls of the outer container, and

a waterproof coating applied to the surfaces defining the air spaces.

10. A sweatproof burial vault comprising an outer container, inner side, bottom, and end walls disposed against the side, bottom, and end walls of the outer container, the majority at least of the inner walls having embossments engaging the outer container to hold the major portions of the inner walls in spaced relation to the outer container to define air spaces therebetween, some of the embossments on the side and end walls being recessed in the walls of the outer container, a waterproof coating applied to the surfaces defining the air spaces, and means providing for drainage of the air spaces.

11. A cover for burial vaults comprising an outer cover, a cover lining disposed on the under side of the outer cover and having its major portion disposed in spaced relation thereto to define an air space therebetween, a waterproof coating applied to the surfaces defining the air space, and means for draining the air space.

12. A cover for burial vaults comprising an outer cover, a cover lining disposed on the under side of the outer cover and having its major portion disposed in spaced relation thereto to define an air space therebetween, said lining being divided into sections and having edges recessed in the cover.

R. A. BURNS.
